THURE AHMÉEN, OF FINSPONG, SWEDEN, ASSIGNEE, BY MESNE ASSIGNMENTS, TO
AKTIEBOLAGET LJUNGSTRÖMS ANGTURBIN, OF STOCKHOLM, SWEDEN.

RADIAL TURBINE OF THE DOUBLE ROTARY TYPE.

1,299,893.

Specification of Letters Patent.

Patented Apr. 8, 1919.

Application filed December 27, 1913. Serial No. 263,573.

To all whom it may concern:

Be it known that I, THURE AHMÉEN, engineer, subject of the King of Sweden, residing at Finspong, Sweden, have invented 5 certain new and useful Improvements in Radial Turbines of the Double Rotary Type, of which the following is a specification.

The invention relates to means for tapping steam from radial turbines of the double rotary type after its having been expanded to a certain degree in the turbine while delivering work.

To this end the radial blade system is divided into two blade groups separated by 15 a suitable packing device and connected on each side of said packing device with a chamber provided with a tapping device, so that the steam, on flowing from one division of the blade system to the other, has 20 to pass through this chamber from which a greater or smaller part of the steam may be carried off.

An embodiment of a double rotary turbine constructed according to the invention 25 is illustrated on the accompanying drawing.

Figure 1 shows an axial cross-section of the turbine and

Fig. 2 a cross-section perpendicular to that of Fig. 1 and on the line II-II in 30 Fig. 1.

In the embodiment shown, 1 designates the turbine casing in which the shafts 2, 3 of the turbine disks 4 and 5 are journaled, said disks being adapted to rotate in oppo- 35 site directions.

By means of a suitable packing associated with the turbine disks the blade system is divided in two divisions, 7 and 8. The packing may comprise a single packing ring 40 carried by one of the turbine disks or it may comprise two or more rings carried alternately by the two turbine disks. In the present instance I have shown two rings 6, one projecting from each turbine disk.

Steam is supplied to the inner one 7 of these 45 two divisions in the ordinary way through an inlet pipe 9, a chamber 10 and openings 11 in the turbine disk. The space between the outermost blade of the inner division 7 and the packing rings 6 is connected with 50 ring-shaped chambers 14 in the turbine casing through a series of openings 12 in the turbine disks and corresponding openings 13 in the surrounding walls of the turbine cas- 55 ing, each of said chambers 14 being provided

with a steam pipe 15 containing a valve 16.

Each chamber 14 is connected through a valve 17 with a chamber 18 concentric with the chamber 14 and said chamber 18 is connected with the space between the packing 60 rings 6 and the innermost blade of the outer division 8 through a series of openings 19 in the wall of the chamber and through corresponding openings 20 in the adjacent turbine disk.

Provided between the turbine disks 4, 5 and the adjacent walls of the turbine casing are the ordinary labyrinth packings, which are broken off opposite to the openings 12, 13 and 19, 20. The valves 17 are adapted to operate automatically so as to be opened and closed directly or indirectly by the pressure or the fall of pressure in the pipes 15. No device for the control of this operation is shown in the drawing, as such controlling 70 devices are already well known. However, at 17^a are indicated alining openings for the passage of stems for valve 17.

The turbine described operates as follows:

The steam entering through the pipe 9 80 flows through the inner division 7 of the blade system, thereby driving the turbine, and enters the chamber 14 after having been expanded to a certain degree, for instance to a pressure of 3 to 4 atmospheres. This 85 pressure depends of course, upon the location of partition packing 6 in the turbine and as is obvious such packing may be placed at a point in the turbine to give the pressure at which it is desired to extract steam. This 90 steam may now be tapped off, if wanted, through the pipes 15 and the valves 16 for any purpose of consumption, in which case the valves 17 are partly closed according 95 to the fall of pressure in the pipes 15. The steam flowing through the partly opened valves 17, enters through the openings 19, 20 into the outer blade system 8 and, while being further expanded, it passes through this blade system into a chamber 21 where 100 a condenser pressure prevails.

If no steam is tapped off from the chambers 14, the valves 17 are fully opened and all steam then flows from the division 7 to the division 8.

In accordance with the provisions of the patent statutes, I have described the principle of operation of my invention, together with the apparatus which I now consider to represent the best embodiment thereof, but 110

I desire to have it understood that the apparatus shown is only illustrative and that the invention may be carried out by other means.

5 Having now particularly described and ascertained my invention and in what manner it is to be performed, I declare that what I claim is:—

10 1. A double rotary turbine comprising a radial blade system, a packing device fastened to a turbine disk and dividing said blade system into two divisions, and a chamber provided with a tapping device and connected to said divisions on each side of said

15 packing device, so as to allow the driving fluid to pass from one division to the other through said chamber.

20 2. A double rotary turbine comprising a radial blade system, a packing device fastened to a turbine disk and dividing said blade system into two divisions, a chamber provided with a tapping device and connected to said divisions on each side of said

packing device, a valve provided in the connection between said chamber and the second division counted in the direction of flow of the driving fluid, and means for controlling said valve by the pressure in said chamber. 25

3. A double rotary turbine comprising two turbine disks rotating in opposite directions, a radial blade system, packing rings fastened to said turbine disks and dividing said blade system into two divisions, two chambers provided in the casing of the turbine, openings provided in the turbine disk and connecting one of said chambers with one of said divisions and the other chamber with the other division and a tapping device connected to the first of said chambers counted in the direction of flow of the driving fluid. 30 35 40

In testimony whereof I affix my signature in presence of two witnesses.

TURE AHMÉEN.
